(57) CLAIM

The ornamental design for a lamp, as shown and described.

DESCRIPTION

FIG. 1 is a perspective view of a lamp showing our new design;

FIG. 2 is a side view thereof, the opposing side being a mirror image;

FIG. 3 is a front view thereof;

FIG. 4 is a back view thereof;

FIG. 5 is a top view thereof;

FIG. 6 is a bottom view thereof;

FIG. 7 is a perspective view of a second embodiment thereof;

FIG. 8 is a side view of FIG. 7, the opposing side being a mirror image;

FIG. 9 is a front view of FIG. 7;

FIG. 10 is a back view of FIG. 7;

FIG. 11 is a top view of FIG. 7; and,

FIG. 12 is a bottom view of FIG. 7.

The broken lines shown in the drawings are included for purposes of illustrating portions of the lamp and form no part of the claimed design.

1 Claim, 12 Drawing Sheets
